ELECTROPLATING APPARATUS

Etienne L. A. Camin and Herbert Kenmore, New York, N. Y., assignors, by mesne assignments, to Kenmore Metals Corporation, New York, N. Y., a corporation of Delaware

Application May 8, 1944, Serial No. 534,543

2 Claims. (Cl. 204—209)

1

This invention relates to a novel apparatus for providing electro-chemical deposits, platings or coatings on a coiled metallic body and the apparatus for producing the same. More specifically this invention relates to an apparatus by which a coiled spring like metal body as of copper or the like may be passed through a series of preparatory plating baths and post-plating treatments rapidly while depositing thereon excellent and relatively thick metal plating.

Previously metal wire has been plated, for example, by passing a very thin metal wire of about .010" diameter through one or a series of baths, the wire being travelled through the bath by bringing it down to guide rollers, out of the bath and into subsequent baths while as much electrical load was applied to the wire as the wire was capable of taking, this being determined primarily by its diameter. In order to lead the wire through these different rolls, it is necessary that the wire be very thin so as to be sufficiently pliable. Because to be pliable such wire must be very thin, only a relatively small electrical load can be applied and a thin metal plating obtained thereon. If a thick metal coat is desired, the time necessary to obtain such coat is impractically long.

It has therefore been the practice to run a great number of such wires simultaneously through such baths and the ordinary production of such fine wire on a large machine such as presently used in this industry constitutes a relatively small amount running in only tens of pounds per day production.

It is mechanically impossible to force a wire of heavy gauge, annealed or not, to take the shape which is necessary to make it travel continuously through such a sequence of operations which are required to obtain a correct plating.

It is the object of the present invention to provide a method and apparatus whereby a heavy gauge wire is carried through a series of baths and electroplated as described hereinafter and to redraw by conventional methods such plated wire to any desired gauge as fine as any ordinary wire can be drawn.

It is an additional object of the present invention to provide a mechanical working of the plating which takes place at the redrawing operation, thus giving to the final, redrawn wire a special quality which cannot be obtained by plating on fine wire without such redrawing after plating.

It is the object of the present invention to provide a method and apparatus whereby from two to five thousand pounds of plated wire can

2

be produced a day and whereby a heavy coat or plating can be obtained in any practical thickness without appreciable reduction of production and quality of the product.

It is a further object of the present invention to provide a method and apparatus whereby relatively high gauge wire can be continuously and efficiently metal plated.

It is a further object of the present invention to provide a method and apparatus whereby coiled wire may be run at high speed through a series of treatments.

It is a further object of the present invention to provide a method and apparatus whereby coiled wire may be run at high speed through an electroplating bath and electroplated at a speed far in excess of any previous speed of travel of wire through electroplating baths.

It is a further object of the present invention to provide a method and apparatus for electroplating metal bodies such as relatively heavy wire continuously and in such a way as to prevent oxidation during the process.

It is a further object of the present invention to provide a novel method and apparatus for electroplating metal bodies of the class described continuously and to provide continuously thereon a sequence or plurality of platings of the same or different metals.

Further objects of my invention will be apparent from a consideration of the drawings and specific description hereinafter set forth.

The objects of this invention are accomplished by moving a coil continuously and rapidly forward by resting the loose coil on a rotating smooth shaft, which, for example, can be a rubber-coated shaft, the rotation of the shaft and the frictional contact of the rotating shaft with the coil acting in conjunction with the spring characteristic of the wire coil so that the coil is rotated by the rotating shaft and moves forward by reason of its helical position and its rotation.

In the drawings,

Figure 1 is a side view and partial cross-section of the apparatus of the present invention.

Figure 2 is a cross-section taken along the line 2—2 of Figure 1 and showing means by which the spacing of the coil is determined and fixed for travelling through the baths.

Figure 3 is a cross-section taken along the line 3—3 of Figure 1 and shows a cross-section of the electroplating tank.

It is a fact that the faster the wire travels, the more efficient and effective is the plating operation. This is both because the speed of the wire

most effectively moves the plating solution in the immediate vicinity of the wire and therefore most effectively replenishes that solution and also because the film of hydrogen gas formed at the plating surface is most effectively dissipated by a fast travelling wire.

The present method and apparatus are particularly and unusually efficient because a heavy gauge wire is employed and hence a higher load of electrical current can be imparted to the operation. More current is used and more wire surface is available for the operation. Hence, a better and faster plating operation can be performed.

Because the operation is continuous and it is not necessary, for example, to dip the coil intermittently in one bath and then withdraw it to another bath by manual or mechanical operation, a plurality or sequence of the same or different metals may be applied effectively. This is because by either spraying solution on the wire as it emerges from one plating bath to the other, or by total immersion of the wire in the plating bath during the succession of bath after bath without manual or mechanical handling during its path of travel, oxidation is completely prevented.

It is of importance in certain cases to avoid such oxidation, for example, if copper is to be plated and to be treated after plating with hydrogen, since such hydrogen chemically unites with the oxide and forms bubbles filled with water vapor underneath the surface and renders the protection of the wire inefficient.

This process may be used for coating any kind of metal such as nickel, silver, copper, iron, or certain alloys of any metallic wire, such as iron, copper, steel or alloys regardless of the cross-sectional shape, such as flat, oval, triangular, rectangular, square, octagon or any polygonal shape.

Referring now more specifically to the drawings in Figure 1 we show a shaft 10 which is generally circular in cross section as can be seen in Figures 2 and 3. The shaft 10 has a rubber cover 11 on the surface thereof. The shaft 10 is rotated through a gear 13 driven by some suitable source of power, not shown.

A coil of wire 12, which, for example, may be copper wire of from $\frac{1}{8}$ " to 1" in diameter and although but a few strands of copper wire 12 are shown at the left or introductory end of the machine, it will be understood that a coil of such wire can and usually is hung on shaft 10 at this point for introduction into the machine.

It will be recognized by those skilled in the art that wire or metal bodies having a thickness of from $\frac{1}{8}$ to 1" could not be led down and around guide members for travelling through a path since this would involve a pliability that metal of this thickness does not have for this type of operation. The wire 12 has a spring or life to it such as is common in coiled wire of this dimension and plays an important part in its movement through the apparatus. The wire 12 passes over and along the shaft 10 because of the rotation of the shaft 10 and its contact with the shaft 10 is maintained and facilitated by the roller 15 which as will be noted in Figures 2 and 3 is circular in cross-section and may have a rubber cover 16. The function of the roller 15 as stated is merely to maintain the wire 12 against the rotating shaft 10 and the roller 15 is not power driven. Depending on the spring of the wire 12 downward pressure can be exerted on the roller 15 by means of pressure adjusting elements 17

and 18 which are screw pressure members, although equivalents thereof may be employed.

So that the shape of the wire coil 12 may be relatively predetermined in its travel through the baths, guide members 20 and 21 which comprise grooved roller guides 22 and 23 fixed by bolts 24 and 25 respectively, are so positioned as to shape the wire coil 12 to a given cross-sectional shape by their action in pressing the wire down towards the shaft 10. To guide the wire and to maintain its loops and its proper spaced relation, we provide a comb guide 27 having slots 28 through which the wire passes. The treating baths which will be more specifically described hereinafter comprise a tank 30 with a series of partitions 31 to comprise separate and independent baths for treating the wire during its travel. The electroplating tank generally denoted as 33 is specifically seen in cross-section in Figure 3. Current is supplied through anodes 34 and 35, the current travelling through the electrochemical bath 36 through the wire 12 to the cathode roller contact 37 supported in a bracket 38 and thence through conductor 39. The contact roller cathode 37 is grooved so as to ride firmly on the wire 12. This function is assisted by the roller guide 40. The wire 12 is maintained at the bottom of the tank in its proper relation by the guide elements formed by the spacer 41 mounted on the rods 42 and 43. Spacer 41 may comprise some electrical insulating material and the rods 42 and 43 are preferably covered with loosely mounted roller sleeves 44 and 45 as shown in Figure 3 which sleeves may be of porcelain or some other electrically and chemically inert material.

The wire 12 then travels through a series of subsequent treatment baths 46, 47 and then out and over the terminal end portion of the shaft 10 which is denoted as 50.

Specifically in the method of the present invention the shaft 10 is rotated through the gear 13 and the rotation of the shaft 10 by reason of friction which is a slipping but constantly applied friction causes the wire coil 12 to rotate over the shaft 10 and hence because of the helical nature of the coil 12 it moves through the machine over the shaft 10 and through the various treatment baths. The rider roll 15 resting on the wire 12 maintains it in contact with the shaft 10 and thus affords the full use of the rotating effect of the shaft 10 on the wire coil 12. The guide slots 28 in the comb guide 27 serve to space and position the wire so that it enters and departs from the various baths in a predetermined manner.

After the various pretreatments of cleaning and the like which are given the wire it enters the electroplating bath 33. There through the anode is imparted a direct current of about from 3-10 volts depending on the gauge of the wire which as pointed out hereinbefore may run from $\frac{1}{8}$ " or up in diameter. The current travels on through the bath through the wire out through the plurality of cathode contacts 37, the current density of the plating ranging from 5 to 50 amps per square decimeter of cathode. The speed of travel of the wire coil is extremely flexible and may be as fast as desired. The speed for example can range from 15 feet per minute up to hundreds of feet per minute.

It is a fact that the faster the wire travels the more efficient and effective is the plating operation. This is both because the speed of the wire most effectively moves the plating solution in

the immediate vicinity of the wire and therefore most effectively replenishes that solution and also because the film of hydrogen gas formed at the plating surface is most effectively dissipated by a fast travelling wire.

The present method and apparatus are particularly and unusually efficient because a heavy gauge wire is employed and hence a higher load of electric current can be imparted to the operation. More current is used and more wire surface is available for the operation. Hence a better and faster plating operation can be performed.

Because the operation is continuous and it is not necessary, for example, to dip the coil intermittently in one bath and then withdraw it to another bath by manual or mechanical operations, a plurality or sequence of the same or different metals may be applied effectively.

The ordinary electrochemical plating bath of commerce may be employed and for example the plating solution may comprise nickel chloride, copper sulphate, silver cyanide, or any other of the common plating baths.

Before the plating operation and to prepare the wire for the plating operation the wire is cleaned by passing it through a series of baths, namely potassium hydroxide, cyanide, hot water, cold water, etc.

The thickness of the plating that may be formed ranges from .00001 to as high as desired. A plating of from .001% thickness to 50% thickness of the body to be plated may be formed.

The end products of this process may be drawn down by the ordinary wire drawing device to as fine a gauge as is desired. The plating formed originally when drawn is unimpaired and exceedingly ductile so that it may be hammered or worked without cracking or breaking. This property in this respect is markedly superior to platings applied to fine gauge wire directly previous to this invention.

In addition to plating wires, tubes of small diameter may be formed by this method of plating metal on to some suitable base material and then removing the plated metal therefrom.

It will be understood that those skilled in the art may modify the apparatus and method here disclosed in various ways for different specific treatments and wire or tube handling problems. The principles of this invention however are specifically exemplified herein and the scope of the invention is to be limited not by the examples set forth but by the appended claims.

We claim:

1. An apparatus for electroplating helically formed, elongated, heavy gauge metal material comprising a longitudinal series of tanks including a tank adapted to contain a cleansing solution and a tank adapted to contain an electroplating solution, a cylindrical roller extending above and along the length of the series of tanks, means for rotating said cylindrical roller, said cylindrical roller adapted to hold a helical series of coils of said elongated metal material to be plated so that the portions of the coils below the roller are suspended within the tanks, a second cylindrical roller for pressing each of the coils which are above said tanks at those portions of

the coils which contact the upper surface of the first cylindrical roller against the surface of the said first roller so that rapid rotation of the said first cylindrical roller produces rapid rotation of the coils and causes the helix of the metal material to feed into the series of baths at one end and out of the series of baths at the other end and so that each coil is rolled under pressure as it emerges from the bath liquid, said tanks being closely spaced so that each coil of the helix has its lower portion submerged in one of the tanks, and electrical contact means adapted to ride on the coils above the surface of the electroplating tank.

2. An apparatus for electroplating helically formed, elongated, heavy gauge metal material comprising a longitudinal series of tanks including a tank adapted to contain a cleansing solution and a tank adapted to contain an electroplating solution, a rubber surfaced cylindrical roller extending above and along the length of the series of tanks, means for rotating said cylindrical roller, said cylindrical roller adapted to hold a helical series of coils of said elongated metal material to be plated so that the portions of the coils below the roller are suspended within the tanks, a second cylindrical roller for pressing each of the coils which are above said tanks at those portions of the coils which contact the upper surface of the cylindrical roller against the rubber surface of the said first roller so that rapid rotation of the said first cylindrical roller produces rapid rotation of the coils and causes the helix of the metal material to feed into the series of baths at one end and out of the series of baths at the other end and so that each coil is rolled under pressure as it emerges from the bath liquid, said tanks being closely spaced so that each coil of the helix has its lower portion submerged in one of the tanks, and electrical contact means adapted to ride on the coils above the surface of the electroplating tank.
